UNITED STATES PATENT OFFICE

118,278

DESIGN FOR A BOOT-SPUR BODY

Frank Dean, San Jose, Calif.

Application July 5, 1939, Serial No. 85,852

Term of patent 14 years

To all whom it may concern:

Be it known that I, Frank Dean, a citizen of the United States residing at San Jose, in the county of Santa Clara and State of California, have invented a new, original, and ornamental Design for Boot-Spur Bodies, of which the following is a specification, reference being had to the accompanying drawing, forming part thereof.

Figure 1 is a side elevation of a boot-spur body showing my new design.

Figure 2 is a view of the same looking toward the right of Figure 1.

Figure 3 is a top plan view of the same.

Figure 4 is a perspective view of the same.

I claim:

The ornamental design for a boot-spur body, as shown.

FRANK DEAN.
